Primary Examiner — Elizabeth Albert*(74) Attorney, Agent, or Firm* — Irina Hass(57) **CLAIM**

The ornamental design for a note dispenser, as shown and described.

DESCRIPTION

FIG. 1 is a perspective view showing the new design for a note dispenser;

FIG. 2 is a right side view thereof;

FIG. 3 is a left side view thereof;

FIG. 4 is a top view thereof;

FIG. 5 is a front view thereof;

FIG. 6 is a bottom view thereof;

FIG. 7 is a rear view thereof; and,

FIG. 8 is a perspective view thereof showing the note dispenser with a note.

The broken lines in FIGS. 1-8 are included for the purpose of showing portions of the note dispenser that form no part of the claimed design.

1 Claim, 5 Drawing Sheets(56)
